HEADBOARD FOR BEDS

Earl C. Wallace, Andrews, and Burl E. Chalmers,
Huntington, Ind., assignors to The Hettrick
Manufacturing Company, Toledo, Ohio, a cor-
poration of Ohio

Application February 8, 1952, Serial No. 18,436

Term of patent 14 years

(Cl. D5—4)

To all whom it may concern:

Be it known that we, Earl C. Wallace and Burl E. Chalmers, citizens of the United States and residents of Andrews, Huntington County, Indiana, and Huntington, Huntington County, Indiana, respectively, have invented a new, original, and ornamental Design for a Headboard for Beds, of which the following is a specification, reference being had to the accompanying drawing, forming a part thereof.

In the drawing:

Figure 1 is a front perspective view of a headboard for beds showing our new design; and

Figure 2 is an edge elevation of the headboard.

The dotted lines showing the bed outline are for illustrative purposes only.

We claim:

The ornamental design for a headboard for beds, as shown and described.

EARL C. WALLACE.
BURL E. CHALMERS.
